UNITED STATES PATENT OFFICE

172,835

TANK-TYPE VACUUM CLEANER OR SIMILAR ARTICLE

George M. Kelly, Sturgis, Mich., assignor to
Kingston Products Corporation, Kokomo, Ind.,
a corporation of Indiana

Application November 16, 1953, Serial No. 27,601

Term of patent 3½ years

(Cl. D9—2)

To all whom it may concern:

Be it known that I, George M. Kelly, a citizen of the United States and a resident of the city of Sturgis, in the county of St. Joseph and State of Michigan, have invented a new, original, and ornamental Design for a Tank-Type Vacuum Cleaner or Similar Article, of which the following is a specification, reference being had to the accompanying drawings, forming a part thereof.

On the drawings:

Figure 1 is a side elevational view of a tank-type vacuum cleaner or similar article, showing my new design;

Figure 2 is a front end elevational view;

Figure 3 is a top plan view;

Figure 4 is a rear end elevational view.

I claim:

The ornamental design for a tank-type vacuum cleaner or similar article, substantially as shown.
